United States Patent Office

Des. 178,154

Patented June 26, 1956

178,154

SPECTACLE TEMPLE

Raymond F. E. Stegeman, Greece, N. Y., assignor to
Bausch & Lomb Optical Company, Rochester, N. Y.,
a corporation of New York

Application December 9, 1955, Serial No. 39,273

Term of patent 7 years

(Cl. D57—1)

FIG. 1

FIG. 2

Fig. 1 is a side elevational view of a spectacle temple, showing my new design.

Fig. 2 is a top plan view thereof.

The characteristic features of my design are shown in full lines on the drawing.

I claim:

The ornamental design for a spectacle temple, substantially as shown and described.
